UNITED STATES PATENT OFFICE.

ALMA GUENTHER, OF NEW YORK, N. Y.

WINDOW PORCH.

Application filed October 17, 1923. Serial No. 669,151.

To all whom it may concern:

Be it known that I, ALMA GUENTHER, a citizen of the United States, and a resident of the city of New York, Stapleton, borough 5 of Richmond, in the county of Richmond and State of New York, have invented a new and Improved Window Porch, of which the following is a full, clear, and exact description.

10 This invention has relation to porches and has particular reference to a window porch structure.

15 The outstanding object of the present invention resides in the provision of a window porch structure which is collapsed and portable and capable of being readily positioned and supported from a window sill to afford an enclosure disposed exteriorly of the window.

20 As a further object the invention contemplates a window porch structure which is comparatively simple and inexpensive to manufacture, strong, durable and safe, and which is capable of association with windows of standard construction.

25 With the above recited and other objects in view, the invention resides in the novel construction set forth in the following specification, particularly pointed out in the appended claims and illustrated in the accompanying drawings, it being understood that the right is reserved to embodiments other than those actually illustrated herein to the full extent indicated by the general 30 meaning of the terms in which the claims are expressed.

In the drawings—

35 Figure 1 is a longitudinal sectional view through the porch in set up condition and associated with a window.

40 Fig. 2 is a rear view thereof removed from the window, with parts broken away and shown in section.

45 Fig. 3 is a fragmentary sectional perspective view of the side covering wall.

Fig. 4 is a detail fragmentary sectional view taken approximately on the line 4—4 of Fig. 1.

50 Fig. 5 is a fragmentary sectional plan view taken on the line 5—5 of Fig. 2.

Fig. 6 is a sectional plan view taken approximately on the line 6—6 of Fig. 1.

Fig. 7 is a fragmentary horizontal sectional view taken on the line 7—7 of Fig. 1.

55 Fig. 8 is a similar view taken on the line 8—8 of Fig. 1.

Fig. 9 is a plan view illustrating the superstructure in collapsed condition and the covering walls partly folded.

Fig. 10 is an enlarged fragmentary sectional view taken approximately on the line 10—10 of Fig. 9.

Referring to the drawings by characters of reference, A designates a wall having a window B therein and which is provided with the usual window sill C. The porch structure constituting the invention consists of a floor or platform 10 of substantially rectangular formation and of an appropriate width to fit within the window. The 70 floor or platform 10 is provided with a depending framework which consists of a pair of downwardly and inwardly inclined side legs 11 extending from the outer or forward end of the floor or base toward the rear and 75 provided with beveled terminals 12 which are designed for flat engagement with the outer surface of the wall A. The legs 11 are braced by rearwardly and upwardly inclined braces 13 extending from and secured to the medial portion of the legs at

80 one end of the brace and secured at their opposite ends to the medial under side of the floor. The legs are further braced laterally by a cross rod 14. The inner or rear 85 end of the floor or platform is provided with a plurality of rows of vertical openings 15 which when aligned with the inner edge of the window sill C are adapted to receive therethrough the retaining members 16 for 90 retaining the floor or platform in associated relation with the window. Preferably the upper surface of the platform adjacent the openings is covered with wear plates 17 having apertures aligning with the openings 15. 95 Under this arrangement it will be seen that

the device is adaptable for association with walls of various thicknesses. An inverted U-shaped frame comprising side arms 18 connected at their upper ends by a cross rod 19 is pivotally attached at the lower free ends of the side arms 18 by the pivots 20 to the bearing members 21 whereby the U-shaped frame may be swung from its vertical set up position downwardly against the 100 floor or platform 10 when the porch is in collapsed condition. Adjacent the rear or inner portion the floor or platform 10 is provided with a pair of tubular standards 22 each of which is pivotally attached as at 105 23 to the bearing members 24. The bearing members 24 are spaced inwardly an appro-

priate distance from the side edges of the platform to dispose the standards 22 out of longitudinal alignment with the side arms 18 to allow for the folding of the standards 22 5 between the side arms 18 when the porch is collapsed. Slidable sleeves 25 are mounted on the standards 22 and are designed to bridge or cover the pivotal point between the standards and the bearing members 24 10 whereby the said standards are retained in a vertical position. The standards 22 are appreciably shorter than the side arms 18 and have telescopically mounted therein for projection therefrom rod sections 26 which when projected therefrom are retained against accidental retraction by a latch 27. The upper end of each section 26 is provided with a reduced upwardly projecting extremity 28 forming a shoulder 29 at its juncture with the section, which shoulder is approximately 20 in alignment with the upper end or cross bar 19 of the U-shaped front frame. A pair of arms 30 are pivotally attached at one end to the cross bar 19 of the U-shaped frame and are provided at their free ends with vertical openings 31 which are designed to fit over the reduced extremities 28 and resting upon the shoulders 29 whereby the upper 25 ends of the rear standards and the inverted U-shaped frame are attached when the porch is in set up condition. In order to further brace and strengthen the structure, a pair of diagonal brace rods 32 are pivotally attached as at 33 to the rotary elements 34 on the bearing members 21, said diagonal brace rods 32 being formed at their free rear ends with heads 35 which are provided with a finger 36 adapted to engage in an opening 37 in the standards 22. 30 The means for enclosing the front and sides of the superstructure of the porch consist preferably of a canvas covering including a front wall section 38 and side wall sections 39 and 40. The lower ends of the 35 walls are provided with a hem 41 forming a continuous tunnel or passageway which is slipped over a U-shaped frame 42. The U-shaped frame embraces the forward and side edges of the platform or floor 10 and the side arms thereof rest within hooks 43 carried by the side edges of the platform. The connecting portion or bight of the U-shaped frame 42 is maintained against upward movement by the turn buttons 44 40 which are pivoted to the upper surface adjacent the forward edge of the floor or platform. The rear terminals of the side arms of the U-shaped frame are axially recessed to receive the bolts 45 which are slidably 45 mounted in bolt carrier 46 attached to the side edges of the floor, said bolts being provided with manipulating knobs 47. The upper edge of the front and side walls is provided respectively with out-turned flaps 48, which flaps are turned over the cross rod 50 and the arms 30. The flaps are retained by separable fastening elements 49 whereby the upper edge of the walls 38, 39 and 40 is secured to the superstructure. The walls 38, 39 and 40 are provided with screened 70 windows 50. In order to permit of the folding of the walls 38, 39 and 40 when the frame or superstructure is collapsed, the said side walls 39 and 40 are detachably connected with the lower wall sections 51, which 75 lower sections 51 and the lower edge of the walls 39 and 40 are provided with eyelets 52 capable of alignment for receiving a rod 53 which is passed therethrough. It is, of course, understood that the rod 53 is withdrawn to disconnect the walls 39 and 40 from their lower sections 51. A roof consisting of sections 54 and 55 having a central hinged connection 56 is adapted to be supported from the superstructure by engaging 80 the openings 57 in said roof sections over upstanding pins 58 provided on the arms 30. 85 The porch when set up and associated with a window affords a substantial, safe enclosure for a child to sleep or play in, or a place for the storage of edibles. Furthermore by removing the roof the device affords a platform for cleaning the outside of the window. When not in use the device may be readily collapsed and removed and stored 90 in a minimum amount of space or readily transported. In folding or collapsing the same, after the roof is removed, the separable fastening elements 49 are disengaged, the rods 53 withdrawn and the wall 38 95 swung downwardly and inwardly with the walls 39 and 40 overlapping each other and the wall 38. The apertures 31 with the arms 30 are disengaged from the terminals 28, permitting the arms 30 to be swung downwardly parallel to the side arms 18 of the inverted U-shaped frame of the superstructure. The latch 27 is manipulated to release the telescopic sections 26 which are then 100 retracted into the standards 22. The angle braces 32 are disengaged from the standards 22 and the inverted U-shaped frame is swung downwardly in parallel relation to the floor or platform 10 together with the arms 30. The standards 22 are swung forwardly to lie inside of the arms 30, while the angle braces lie outside of the arms 18. The walls 38, 39 and 40 in folded condition are then 105 folded over parallel to the floor or platform overlying the collapsed superstructure, 110 I claim: 1. A window porch comprising a platform having means for attaching and supporting the same from the window sill, a collapsible superstructure attached to the platform including an inverted U-shaped member pivotally attached at its lower end to the forward or outer end of the platform and capable of downward folding thereon, a pair of longitudinally extensible standards 115 120 125 130

- pivots attached to the platform adjacent its rear or inner end, means for holding said standards in extended position, means for retaining said standards in vertical position, 5 arms pivots attached at one end to the bight of the U-shaped member, means at the free ends of said arms engageable with the upper ends of the standards, and a foldable covering for said collapsible superstructure having means for detachably associating the same therewith and with the platform.
2. A window porch comprising a platform having means for attaching and supporting 15 the same from the window sill, a collapsible superstructure attached to the platform including an inverted U-shaped member pivotally attached at its lower end to the forward or outer end of the platform and capable of downward folding thereon, a pair of longitudinally extensible standards 75 pivotally attached to the platform adjacent its rear or inner end and capable of downward folding thereon, means for holding said standards in extended position, means for retaining said standards in vertical position, 80 arms pivotally attached at one end to the bight of the U-shaped member, means at the free ends of said arms engageable with the upper ends of the standards, and auxiliary angle braces pivotally connected with the 85 forward portion of the platform and detachably engageable with the rear standards for bracing the structure, and a foldable covering for said collapsible superstructure having means for detachably associating the 90 same therewith and with the platform.
3. A window porch comprising a platform having means for attaching and supporting the same from the window sill, a collapsible superstructure attached to the platform including an inverted U-shaped member pivotally attached at its lower end to the forward or outer end of the platform and capable of downward folding thereon, a pair of longitudinally extensible standards 95 pivotally attached to the platform adjacent its rear or inner end, means for holding said standards in extended position, arms pivotally attached at one end to the bight of the U-shaped member, means at the free ends of said arms engageable with the upper ends of the standards, a foldable covering for said collapsible superstructure having means for detachably associating the same therewith and with the platform, the said detachable means of 100 connection comprising a U-shaped bar embracing the forward and side edges of the platform, a hem at the lower edges of the covering providing a tunnel for receiving the U-shaped bar, means for detachably associating the U-shaped bar in its embracing position with the platform, and foldable portions at the upper end of the covering adapted to be bent over the bight of the U-shaped member and the arms pivotally attached thereto, and separable fastening elements 105 therefor.
4. A window porch comprising a platform having means for attaching and supporting the same from the window sill, a collapsible superstructure attached to the platform including an inverted U-shaped member pivotally attached at its lower end to the forward or outer end of the platform and capable of downward folding thereon, a pair of longitudinally extensible standards 110 pivotally attached to the platform adjacent its rear or inner end and capable of downward folding thereon, means for holding said standards in extended position, means for retaining said standards in vertical position, 115 arms pivotally attached at one end to the bight of the U-shaped member, means at the free ends of said arms engageable with the upper ends of the standards, and a foldable covering for said collapsible superstructure having means for detachably associating the same therewith and with the platform.

ALMA GUENTHER.
